DISPLAY DEVICE

Raymond E. Neifert, Brooklyn, N. Y., assignor to
 J. A. Deknatel & Son, Inc., New York, N. Y., a
 corporation of New York

Application September 13, 1932
 Serial No. 632,998

2 Claims. (Cl. 211—1)

This invention relates to display devices and more specifically to a display rack for use upon counters of retail stores and show rooms for displaying merchandise.

5 One of the objects of the invention is the provision of a display rack or stand of the character indicated, particularly adapted for prominently displaying beads, jewelry and the like.

Another purpose is the construction of a device upon which may be simultaneously displayed necklaces, rings, bracelets, brooches, earrings, clips and pendants in a manner readily visible so as to attract the attention of a prospective purchaser.

15 Still another aim is the formation of a display stand embodying all the features referred to, yet being of simple construction and characterized by relatively few parts.

All of the above will be obvious from the description hereinafter appearing when considered in conjunction with the drawings appended hereto and made part hereof, and in which:

Fig. 1 is a front elevation of one embodiment of the invention adapted to effectively and simultaneously display necklaces, bracelets, rings, brooches and earrings;

Fig. 2 is a side elevation of the form of the invention shown in Fig. 1;

Fig. 3 is a sectional view taken on line 3—3 of Fig. 1;

Fig. 4 is a front elevation of a second embodiment of the invention in somewhat modified form;

Fig. 5 is a top plan view of the arms which support the necklaces; and

35 Fig. 6 is a sectional view taken on line 6—6 of Fig. 4.

Referring first to the form of the invention shown in Figs. 1, 2 and 3, the reference numeral 10 designates a substantially flat rectangular base 40 adapted to rest on a counter or show case. Secured to and rising centrally from this base is an article supporter 11 having side walls 11^a, 11^b, a rear wall 11^c and a front wall 11^d. The upper surface of the holder 11 is arranged to extend angularly with respect to base 10 and is divided so as to form a series of stepped display surfaces 12, 13, and 14, respectively, of varying areas. The surface 12 is of less area than either 13 or 14 and is formed with a plurality of apertures 15 for partially receiving therewithin articles of jewelry, such as rings. These apertures it will be noted extend in alignment in spaced relationship from end to end and centrally of the surface 12. In view of the fact that but a portion of the circumference of each ring is displayed, the display space

required for a number of rings is small and accordingly the area of the surface 12 need not be very great.

Situated below the surface 12 and in stepped relationship thereto is a display surface 13 of larger area which has a plurality of elongated openings 16 for securing brooches or the like thereto. These brooches require more display space and accordingly the area of the surface 13 is greater than that required for displaying the rings, as described above.

The display space 14 projects in stepped relationship to 13 and extends downwardly therefrom to the front wall 11^d of the article supporter. A series of apertures 17 is formed within and across the surface of the display area near its upper edge so that a plurality of earrings may be secured therein, yet providing ample room for receiving the pendant portions of the rings on the area 14. Display areas 12, 13 and 14 are preferably covered with velvet of a distinctive color to constitute a background for prominently displaying jewelry placed thereon.

An arm 18, semi-circular in cross-section and having a corrugated or grooved surface 18^a is secured to the walls 11^a, 11^b, and 11^c of the article supporter to extend above the base and substantially parallel thereto. Upon this may be hung bracelets, and if these be of the beaded variety, the individual beads will tend to rest in the grooves 85 of the corrugated surface 18^a so as not to permit the string on which the beads are strung to contact the arm so as to avoid directly supporting the entire weight of the bracelet on the string. The curve of this arm is so constructed that the bracelets hang on it approximately as they would on a woman's arm.

A standard 19 provided with braces 19^a, 19^b extends vertically upward from the rear wall 11^c of the article supporter. Secured by means of brackets 20, 20^a to the uppermost portion of the standard is an arm or arms 21 projecting substantially parallel to the arm 18 equidistantly on each side of the standard 19. A series of pegs 22 provided with stops 23 are fastened to the arm 21 in spaced relationship and at right angles thereto. The surfaces of these pegs are also corrugated in a manner similar to the arm 18 and are adapted to receive necklaces or strings of beads thereon to hang therefrom.

The form of the invention shown in Figs. 4, 5 and 6 is characterized by a flat base 30 which may be square, as shown, or circular, rectangular, or any other desired shape. Secured centrally thereto is a pivot pin 30^a for rotatably support-

ing the main portion of a display rack generally designated as D. The latter embodies four article supporters 31, 31^a, 31^b, and 31^c symmetrical-
ly arranged and attached to a standard S. Each
5 article supporter is constructed similar to the
supporter 11 described in the previous embodiment,
with the one exception that the stepped
display surfaces are of equal area. The sup-
porter 31 is provided with apertures 31' on its
10 display surfaces for securing earrings therein;
the supporter 31^a has elongated openings 31''
on its display areas for fastening brooches there-
in; the supporter 31^b has apertures 31''' for
holding rings on its display surfaces; and the
15 supporter 31^c is adapted for clips or the like on
its display portion. Also secured to the standard
S and radiating therefrom between the article
supporters are arms 35, 35^a, 35^b, and 35^c, identical
in construction with the arm 18, previously de-
20 scribed.

The standard S, in addition, has secured there-
to and radiating therefrom at the upper end
thereof a plurality of rods 40 provided with pegs
41 for supporting necklaces therefrom.

25 From the above description it will be seen that
I have provided a display device ideally adapted
for simultaneously and effectively displaying
beads and jewelry. In the form of the invention
shown in Figs. 4 to 6, inclusive, it will be ap-
30 preciated that the standard S may be rotated on

its pivot pin to bring any desired portion of the
display device into view.

It will be further understood that the invention
is not limited to the precise details of con-
struction as herein set forth, as the invention may
be adapted for other uses than supporting beads
80 and the articles of jewelry enumerated, and that
consequently variations may be made in the
fastening means for retaining the articles to be
supported in connection with the inclined sur-
faces of the supporters. The invention may be
85 therefore said to cover all such modifications as
fall fairly within the scope of the following
claims.

What I claim is:

1. A display device comprising a base having
a holder thereon, the holder being provided with
means for displaying a plurality of articles, an
arm supported above the base substantially par-
90 allel thereto, said arm having a corrugated upper
surface with the corrugations extending longi-
tudinally of the arm.

2. A display device comprising a base having a
holder thereon, the holder having a series of
stepped surfaces provided with means for dis-
100 playing various articles, an arm supported above
the base substantially parallel thereto, said arm
having a corrugated surface with the corruga-
tions extending longitudinally thereof.
